AUTOMATIC JOINT BREAKER

Filed April 21, 1930

Inventor:
PEXTON F. MURRAY.
By *Maxim P. Smith*
Attorney.

UNITED STATES PATENT OFFICE

PEXTON F. MURRAY, OF MONTEBELLO, CALIFORNIA

AUTOMATIC JOINT BREAKER

Application filed April 21, 1930. Serial No. 445,878.

My invention relates to an automatic joint breaker of the particular type disclosed in my co-pending application for patent filed May 15th, 1929, Serial No. 363,308.

5 The principal objects of my present invention are, to generally improve upon and simplify the construction of the joint breaker disclosed in my aforesaid co-pending patent application, as well as other similar forms of 10 joint breakers or "catheads" and further, to provide a joint breaker that may be conveniently utilized with practically all standard forms of rotary well drilling rigs and to construct the joint breaker so that it will permit 15 the tongs with which it is associated to be applied to the tubes or pipes in any position, thereby greatly facilitating the work incident to the breaking of pipe joints and the like.

20 Further objects of my invention are, to provide a relatively simple, practical and inexpensive cathead or joint breaker that is entirely automatic in its releasing action and further, to provide a joint breaker that is 25 strong and substantial in structure and which may be conveniently thrown into operation so as to exert a pull or jerk upon the line that is connected to the pipe tongs.

With the foregoing and other objects in 30 view, my invention consists in certain novel features of construction and arrangement of parts that will hereinafter be more fully described and claimed and illustrated in the accompanying drawings, in which:

35 Fig. 1 is an elevational view of a cathead or joint breaker constructed in accordance with my invention and with parts thereof broken away and in section.

Fig. 2 is an elevational view looking in the 40 direction indicated by the arrow 2 in Fig. 1 and showing a portion of the curved rail broken away.

Referring by numerals to the accompanying drawings which illustrate a practical embodiment of my invention, 10 designates one of the jack posts of a rotary well drilling rig and secured to said jack post is a bearing 11 in which is journaled a constantly rotating shaft 12 and secured upon the end of the latter is 45 a spool or drum 13, upon which is adapted

to wind, a chain or cable that may be used in drilling operations or for the operation of parts of the drilling rig.

Formed integral with or fixed to the inner portion of the spool or drum 13 is a sheave 14, provided in its periphery with a channel 15, and formed on the periphery of said sheave within said channel is a lug or shoulder 16.

Secured in any suitable manner to the outer face of the jack post 10 are the end portions 17 of a substantially semi-circular rail 18 that lies immediately adjacent to the periphery of the sheave 14 and said rail is concentric with the axis of shaft 12.

Formed in the outer face of the rail 18 is a groove or channel 19 that is approximately half round in cross section.

Arranged to slide freely upon the semi-circular rail 18 is a block or runner 20, to the underside of which is connected one end of the cable 21, that is utilized in the operation of the pipe, tongs or other parts of the drilling paraphernalia that may be advantageously actuated by pulling strains of a 75 cable, chain or the like.

Formed integral with or fixed to the lower end of rail 18 is a block 22, through the lower portion of which is formed an opening for the accommodation of the cable 21 and journaled in the lower portion of this block is a roller 23 that functions as a rolling support for the cable as it passes onto and from the cathead.

Block 22 is provided with a flat front face 85 24 that functions as a stop against which the rear end of the block or runner 20 engages when the same is at the lower end of its travel on rail 18.

Hinged on the upper front portion of the 90 runner 20 is one end of a pawl or dog 25, the free end of which is adapted to engage against shoulder 16 on the periphery of sheave 15 and secured to pins 26 that project outwardly from the sides of the pawl or dog 95 27, the lower ends of which are retractile springs 28 that project from the sides of runner 20. The springs 27 normally hold the pawl 25 inwardly against the upper face of the runner 20 so that the 100

end of the pawl is out of engagement with the periphery of the sheave.

Fulcrumed on the front upper portion of block 22 is a small bell crank 29, the end of the long arm thereof occupying a position beneath the free end of pawl 25 and secured to this long arm of the bell crank is one end of a retractile spring 30 that normally exerts a pull on said bell crank so as to hold the long arm thereof away from the pawl 25.

Secured to the short arm of bell crank 29 is a flexible member 31 such as a cable that extends over suitably located pulleys 32 to a point convenient to the hand of an operator.

Formed integral with the upper end portion of the semi-circular rail 18 and arranged on the inside thereof are concentric fingers 33 provided on their forward upper portions with cam surfaces 34 that are adapted to engage the pins 26 on runner 20 as the latter approaches the upper end of its travel.

Under normal conditions the pull upon the jerk line or cable 21 holds runner 20 on rail 18 immediately in front of block 22 and the springs 27 retain pawl 25 out of engagement with the shoulder 16. When it is desired to impart a pull or jerking movement to the cable, an operator pulls on flexible member 31, thereby swinging bell crank 29 upon its axis and moving the free end of pawl 29 into the path of travel of shoulder 16 on sheave 15.

It will be understood that shaft 12 and the drum and sheave carried thereby are constantly rotating and as a result of the engagement between shoulder 16 and pawl 25, the latter and the runner 20 to which the pawl is hinged will be caused to travel upwardly on the curved rail 18, thereby imparting a jerk or pull to line 21 and the latter following the runner 20 will pass upwardly through the groove or channel 19 in rail 18.

As the runner approaches the upper end of the semi-circular rail 18, the pins 26 that project from the sides of said runner will engage on the cam surfaces 34 of fingers 33 and such action will pull the free end of the pawl inwardly toward the runner so as to automatically effect a disengagement between said pawl and the shoulder 16 and following such disengagement, the pulling strains resulting from the resistance offered by the tongs or member to which the jerk line 21 is connected, will quickly return the runner 55 and pawl carried thereby to the lower end of the rail.

The downward travel of the runner is limited by the rear face 24 of block 22 and the retractile springs 27 pull the pawl into position against the upper surface of the runner and the parts occupy such positions until the pawl is again swung outwardly by bell crank 29 that is actuated by the pull cord 31.

Thus it will be seen that I have provided

a cathead or joint breaker for rotary oil well drilling rigs that is relatively simple in construction, inexpensive of manufacture, automatic in its release under ready control of an operator and which joint breaker is very effective in performing the functions for which it is intended.

It will be understood that minor changes in the size, form and construction of the various parts of my improved automatic joint breaker may be made and substituted for those herein shown and described without departing from the spirit of my invention, the scope of which is set forth in the appended claims.

I claim as my invention:

1. In an automatic joint breaker, the combination with a constantly rotating sheave, of a substantially semi-circular fixed track disposed adjacent to and concentric with said sheave, a runner mounted for sliding movement on said track cooperating means on said sheave and runner for effecting a driving engagement between the sheave and runner for a portion of a complete revolution of said sheave and a jerk line connected to said runner.

2. A joint breaker, as set forth in claim 1, means for effecting a driving engagement between the sheave and runner, and means for automatically disengaging the driving connection between said sheave and runner.

3. In an automatic joint breaker, a sheave mounted for rotation, a shoulder on said sheave, a semi-circular track rail positioned adjacent to and concentric with said sheave, a runner mounted for sliding movement on said track rail, a jerk line connected to said runner and a pawl hinged to said runner and adapted to be engaged by the shoulder on the sheave.

4. A joint breaker, as set forth in claim 3, and with manually operable means for moving said pawl into the path of travel of the shoulder on said sheave.

5. A joint breaker, as set forth in claim 4, manually operable means for moving said pawl into the path of travel of the shoulder on said sheave and means for automatically disengaging said pawl from said shoulder.

6. In an automatic joint breaker, the combination with a sheave mounted for rotation, of a semi-circular track rail positioned adjacent to and concentric with said sheave, the outer face of which rail is provided with a groove, a runner mounted for sliding movement on said track rail, a jerk line connected to said runner and adapted to traverse the groove in the track rail and means for effecting a driving engagement between the sheave and runner for a predetermined portion of a complete rotation of said sheave.

7. A joint breaker, as set forth in claim 6, and with means for automatically breaking

the driving engagement between said runner and sheave.

8. In an automatic joint breaker, the combination with a rotary member of a track rail arranged concentric with and partially surrounding said rotary member, a runner mounted for sliding movement upon said track rail, a jerk line connected to said runner and manually operable means for effecting a driving connection between said runner and sheave.

9. A joint breaker, as set forth in claim 8, with means for automatically breaking the driving engagement between said sheave and runner.

10. A cathead structure comprising a winding sheave having a winding surface for a line, a coupler abutment on said sheave, a line having a coupler for engagement by said abutment whereby to anchor said line to said sheave, a frame partially encompassing said sheave, said frame having a release member to engage said coupler and lift the latter from engagement with said abutment at the end 25 of its travel along said frame, there being an entry end on said frame, a retaining rail on said frame to maintain said coupler in engagement with said abutment during travel of said coupler from the entry end of the 30 frame to said release member, and means to initially place said coupler in engagement with said abutment.

11. In an automatic joint breaker, a sheave mounted for rotation, a shoulder on said sheave, a substantially semicircular track rail positioned adjacent to and concentric with said sheave, a runner mounted for sliding movement on said track rail, a jerk line connected to said runner, means on said runner adapted to be engaged by the shoulder on the sheave, and manually operable means for effecting a driving connection between the last named means and said shoulder.

12. In an automatic joint breaker, the combination with a rotary member, of a track rail arranged concentric with and partially surrounding said rotary member, a runner mounted for sliding movement upon said track rail, a jerk line connected to said runner, manually operable means for effecting a driving connection between said runner and sheave, and means for automatically breaking the driving engagement between said sheave and runner.

55 In testimony whereof I affix my signature.
PEXTON F. MURRAY.
